UNITED STATES PATENT OFFICE.

WILLIAM CAMERON, OF CHICAGO, ILLINOIS, ASSIGNOR TO CAMERON CAN MACHINERY COMPANY, OF CHICAGO, ILLINOIS, A CORPORATION OF ILLINOIS.

CAN-TESTING MACHINE.

Application filed December 4, 1922. Serial No. 604,691.

To all whom it may concern:

Be it known that I, WILLIAM CAMERON, a citizen of the United States, residing at Chicago, in the county of Cook and State 5 of Illinois, have invented certain new and useful Improvements in Can-Testing Machines, of which the following is a specification.

This invention relates to improvements 10 in apparatus for testing cans by filling them with air under pressure and submerging the filled cans in a tank of water wherein the operator can detect a leaky can by the air bubbles rising therefrom in the 15 water.

The invention aims to improve the construction and operation of machines of this general type, and with this end in view, contemplates novel means for feeding the 20 cans successively to a rotating carrier, novel means for clamping and sealing the cans on the carrier, novel manually controlled means whereby the leaky cans may be separated from the good cans, novel means for 25 discharging both the good and leaky cans from the carrier, and other novel features which will become apparent as the invention is disclosed more in detail hereafter.

An important feature of the invention, 30 however, resides in the fact that the cans are delivered to the carrier at one side thereof, are carried downwardly through and are submerged in a tank disposed around the lower portion of the carrier, 35 and are discharged from the carrier at the opposite side of the tank from which they were delivered to the carrier. This construction provides a simple, efficient, economical, and rapid machine, and possesses 40 many advantages over those machines in which the cans are fed to and discharged from the carrier at the same side thereof.

For the purpose of facilitating an understanding of my invention, I have illustrated on the accompanying drawings a preferred embodiment thereof, from an inspection of which, when considered in connection with the following description, the

principles of my invention and many of its inherent advantages should be readily appreciated.

Referring to the drawings:

Fig. 1 is a side elevation of a machine embodying my invention;

Figs. 2 and 3 are face views of the can 55 holder, closing and opening cams, respectively;

Fig. 4 is a view looking toward the left at Fig. 1, certain portions of the carrier 60 being broken away;

Fig. 5 is a fragmentary sectional view on the line 5—5 of Fig. 4;

Fig. 6 is a sectional view on the line 6—6 of Fig. 1;

Figs. 7 and 8 are sectional views looking 65 toward the left and right, respectively, on the line 7—8 of Fig. 6;

Fig. 9 is an enlarged view of one of the manually controlled devices by which the leaky cans are separated from the good 70 cans;

Fig. 10 is an enlarged fragmentary view of the mechanism by which the cans are fed to and positioned on the carrier; and

Fig. 11 is a similar view of the mechanism 75 for discharging the cans from the carrier.

Referring now to the drawings more in detail, reference character 12 indicates the base of the machine upon which the liquid 80 containing tank 13 and the various operating parts of the machine are carried. The tank is illustrated herein as being cast integrally with the base, although, manifestly, it may be made of sheet metal or otherwise constructed independently of the base. A standard 14, rising from one side of the tank, is adapted to carry the chute 15 which delivers the can bodies to the machine, and also the cam plate 16 upon the face of 85 which the cam bars 17 and 18 are mounted, the purpose of which will be later explained. At the opposite side of the tank another standard 19 carries the leaky can delivery chute 21, the good can delivery 90 chute 22, and the cam plate 23, upon the

face of which are mounted the cam bars 24 and 25, for a purpose which will be later explained.

In suitable bearings 26 and 27, carried upon the frame structure 28 of the machine, there is rotatably mounted a hollow shaft 29 which supports the hub 31 of a large annular carrier fixed to and adapted to be rotated by the hollow shaft 29, which, in turn, has fixed thereon between the bearings 26 and 27 a worm wheel 32 meshing with and driven by a worm 33, which receives its power from any suitable source.

Within the hollow shaft 29 there is disposed a stationary tubular axle or shaft 35, between which and the enlarged surrounding forward end of the shaft 29 there is disposed a bearing sleeve 36. The forward end of the shaft 35 is closed by a screw plug 37, or other means, and its rear end is closed by a hollow cap 38, screwed into the end of the shaft and connected by a pipe 39 with a supply of air under suitable pressure. A thrust collar 41, fixed to the shaft 35 by a key 42, is interposed between the cap 38 and the end of the shaft 29, and also of the bearing 27.

A stationary plate or disk 43 is mounted upon the shaft 35 in front of the carrier hub, and an adjusting ring 44 is threaded onto the shaft 35 forwardly of this disk. By rotating this ring upon the shaft, the position of the disk 43 longitudinally of the shaft may be regulated, and in order to further assist in retaining the disk in position on the shaft, a set screw 45 is employed. Turning movement of the disk on the shaft is prevented by a spline 46.

Between the disk 43 and the opposed end 40 of the carrier hub 31, there is interposed a plate 47, which is urged into close fitting engagement with the disk 43 by a plurality of coiled expansion springs 48, seated in opposed sockets formed in the plate and hub. The plate 47 is rotatable upon the shaft 35 with the carrier hub, and to effect this rotation the plate is equipped with a plurality of studs 49 riveted to the plate, and projecting into sockets 51 formed in the end of the hub. The plate is therefore rotated with the carrier and is urged into snug engagement with the disk 43 by the springs 48.

Air under pressure, which enters the bore 55 of the shaft 35 from the supply pipe 39, is conducted from said shaft by an elbow pipe 52 to a laterally elongated port 53 formed in the disk 43. The plate 47 is provided with a series of angle shaped ports 54, connected by nipples 55 with pieces of hose 56, each of which is connected at its other end by a nipple 57 with a port 58 extending through the stationary head 59 of one of the can clamping and holding members, whereby 65 this air is conducted to the interior of a

can body clamped in such holder. The elongated port 53 is of sufficient length to permit a flow of air under pressure into a can body so as to place said body under internal pressure during the registry of a port 54 with said port 53, and after the port 54 has passed beyond the port 53, the port 54 will be sealed so as to preclude the escape of air by reason of the close fit between the contacting faces of the disk 43 and the plate 47.

The can carrier comprises a large circular rim 61 carried by a plurality of spokes 62 radiating from the carrier hub 31. This rim comprises, as will be apparent from Fig. 4, a rear member 63 and a forward member 64, these two rim members being rigidly clamped together in any suitable manner.

The carrier rim is provided with a multiplicity of can holding and clamping devices, each of which comprises a stationary member 59 carried upon a shaft or rod 65, which is longitudinally adjustable in the rim member 63, and is adapted to be locked in adjusted position by a set screw 66. This member is adjustable to accommodate the holder to cans of various lengths, and is faced with rubber or other suitable material 67 (Fig. 4), adapted, when forced against the open end of a can body 68, to seal the open end thereof.

The other clamping member 69 of each holder is carried by a rod 71 slidably mounted in the rim member 64, and the outer end of this rod is connected by a link 72 with a bell crank arm 73 adapted to swing from the clamping position shown in full lines in Fig. 5 to the release position indicated in dotted lines in said figure. It will be observed that when in clamping position, the connection between the link 72 and the bell crank is disposed just beyond a line intersecting the pivot of the bell crank and the pivotal connection between the link 72 and the rod 71, so that the clamp will automatically remain in the closed position shown. In order to limit swinging movement of the bell crank in a counter-clockwise direction, viewing Fig. 5, its outer end is equipped with an abutment 74 adapted to engage the projecting ear 75 of the rim member 64, this abutment being adjustably mounted in a split stud 76, best shown in Fig. 9, which is drawn together to clamp the abutment in adjusted position by a clamping screw 77.

Each bell crank member carries at its free end a post 78, which is slidable longitudinally in its bearing, the post being provided at its inner end with a knob 79, and at its outer end with an anti-friction roller 81. A coiled spring 82, snugly embracing the post 78, frictionally holds the post in the position shown in Fig. 9, but upon depre-

sion of the post by pushing downwardly upon the knob 79, the spring will be slightly expanded diametrically so as to release the post and permit its unrestricted further longitudinal movement.

The purpose of these posts will now be explained. Referring to Figs. 1 and 2, it will be observed that the cam plate 16, equipped with the cam bars 17 and 18, is disposed in the path of travel of the rollers 81, and that upon rotation of the carrier in a counter-clockwise direction, viewing Fig. 1, the rollers will successively engage first the inclined portion 83 of the cam 18, which will swing the bell crank 73 into the dotted line position of Fig. 5, so as to retract the clamping head 69 and permit a can body to be delivered from the chute 15 into position between the clamping heads 69 and 59. Blocks 84 (Fig. 10) disposed between successive clamping stations on the carrier rim insure that the can bodies will enter between the rim members in proper position to be clamped between the clamping heads. These blocks are detachably mounted on the rim and may be replaced by larger or smaller blocks to accommodate the apparatus to smaller or larger diameters of can bodies. After a holding station has received its can body from the chute 15, further travel of the carrier will bring the roller 81 into engagement with the cam 17, which, as will be apparent from Fig. 2, will swing the roller, and thereby the bell crank 73, in the opposite direction to the full line position shown in Fig. 5, in which position it becomes automatically locked, as previously explained, to clamp the can body snugly between the heads 59 and 69, as shown in Fig. 4. It should be observed that the tail portion 85 of the cam 17 is shaped to engage the rollers 81, should the machine accidentally be reversed. This insures that the parts will be properly positioned in their travel past the chute mechanism so that no breakage of parts may be caused.

The mechanism which delivers the can bodies to the carrier and insures the proper position of the cans with respect to the clamping heads is most clearly shown in Figs. 1 and 10, and referring thereto, it will be observed that an arm 86, carried by the hollow axle 35, is provided at its left hand, viewing Fig. 1, with a bracket 87 upon which an arcuate guard plate 88 is mounted. The bracket 87 is secured to the arm 86 by bolts 89 passing through elongated slots in the bracket so that the guard plate may be adjusted toward or from the perimeter of the carrier to accommodate can bodies of various diameters. A can body entering the carrier from the chute 15 rests upon the block 84 and its inward movement is limited by the guard plate 88. To insure that the can body will be engaged with the guard

plate, there is mounted immediately beneath the delivery end of the chute 15 an arm 89 fulcrumed at 91 upon a bracket 92, the lower end of this arm being disposed in the path of travel of the can bodies, and yieldingly urged into this position by a tractile spring 93. An adjustable abutment 94 limits the projection of the lower end of the arm into the path of the can bodies. To insure against accidental jamming of the can bodies against the delivery end of the chute 15, this end section 95 is pivotally mounted at 96 and is normally retained in the position shown in Fig. 10 by a helical spring 97 surrounding the pivot pin and attached at one end to the chute structure, and at its other to the section 95, so that this section is yieldingly retained in position. The can body is therefore, by the conjoint action of the block 84, the guard plate 88, and the spring pressed arm 89, accurately aligned between the clamping heads of the can holder, and when thus aligned the clamping head 69 will be moved by the cam 17 into clamping position, as previously explained, thereby firmly clamping and holding the can.

After the can body has been clamped, as just explained, air is admitted thereto as the port 54, communicating with the interior of the clamped can body, passes the compressed air supply port 53. The can body is therefore filled with air under pressure, and when thus filled, it is, by the continued travel of the carrier, submerged in the water in the tank 13. The operator, who stands at the front side of the machine, observes the passage of the can bodies through the water and if bubbles arise from any body, the operator pushes downwardly upon the knob 79 of the holder in which the defective can is carried, thereby lowering the roller 81 so that it will be engaged, as the body leaves the tank, by the cam 25, while those holders containing good cans will not be thus manipulated and will be discharged from the machine at another point, as will now be explained.

Referring now to Figs. 1 and 3, it will be observed that the cam plate 23, comprises two portions; namely, 98 and 99, disposed at different radial distances from the center of the carrier. The cam 24 is disposed in the path of travel of the rollers 81, which have not been depressed by the operator, while the cam 25 is disposed in the path of travel of those rollers which have been depressed by the operator upon the discovery of leaky cans carried by such holders. Due to the difference in radial distances of the cams 24 and 25 from the center of the carrier, the rollers 81, which have not been depressed, will pass over the cam 25 and will not be affected thereby.

Considering first one of the holders con-

taining a perfect can, the roller 81 thereof will pass above cam 25 and be engaged by cam 24, which will swing the bell crank 73 so as to retract the head 69 and release the cam. This release will occur at about the time the can reaches the delivery chute 22, and to insure that the can will leave the carrier and enter this chute I have provided a kickout lever 101 (Fig. 11), the free end 10 of which is yieldingly projected into the path of travel of the can bodies by a tractile spring 102 so that as the released can body is brought into engagement with this lever, the body will be projected by the lever from 15 the carrier into the chute 22.

The imperfect cans, however, by reason of the fact that the posts of their holders have been depressed to dispose their rollers 81 in the plane of the cam 25, will be released 20 by this cam and discharged from the carrier into the chute 21 by the kickout lever 103, similar in construction and operation to the lever 101, and likewise actuated by a tractile spring 104. After the imperfect can has 25 been discharged, the end of the post 78 will ride up the incline 105 of the cam plate 23, thereby restoring the post to normal position.

In order to prevent water from the wet 30 holders from dripping upon the operator as the carrier is revolved, I have mounted beneath the upper portion of the carrier a drip plate 106, which is supported upon posts 107 carried by the arm 86. The right-hand end of this arm is equipped with a bracket 108 upon which the kickout levers are mounted, as will be apparent from 35 Fig. 11.

It is believed that my invention, its construction, mode of operation, and many of 40 its inherent advantages will be understood from the foregoing without further description, and while I have shown and described a preferred embodiment of the invention, 45 it should be manifest that the principles thereof are capable of embodiment in a machine differing materially in structural details from that illustrated and described, and without departing from the essence of 50 the invention, as defined in the following claims.

I claim:

1. In a can testing machine the combination of a rotatable carrier, a plurality of 55 can holders mounted thereon, separating blocks interposed between successive holders, a guard plate at one side of the carrier disposed inside the path of travel and in proximity to the can holders, a can delivery 60 chute opposed to said guard plate, and a spring pressed arm beneath said chute for positioning the cans in said holders.

2. In a can testing machine the combination of a rotatable carrier, a plurality of 65 can holders mounted thereon, a can delivery

chute for delivering cans to said holders, the delivery end of said chute being yieldably mounted, a yieldably mounted arm in proximity to the chute for urging the cans into position in said holders, and a guard 70 plate cooperating with said arm to center the cans in the holders.

3. In a can testing machine the combination of a rotatable carrier, a plurality of can 75 holders mounted thereon, each holder comprising a stationary head adjustably mounted on said carrier and a movable head opposed to said stationary head, a bell crank member mounted on the carrier in proximity to each holder, a toggle connection between 80 each bell crank member and the movable head of the holder, a post slidably carried by each bell crank member, a spring for frictionally holding each post in position, and a stationary cam in the path of travel 85 of said posts whereby said bell crank members are actuated to close said holders.

4. In a can testing machine the combination of a carrier, a plurality of can holders 90 mounted thereon, each comprising an adjustable normally stationary head and a movable head, a bell crank member, a connection between said member and said movable head, said connection being adapted to automatically lock said movable head in can 95 clamping position, a post slidably mounted in each bell crank member, and a coiled spring surrounding each post and adapted to frictionally hold the same against displacement, said spring being constructed to 100 release the post upon initial movement of the post.

5. In a can testing machine the combination of a rotatable carrier provided with a plurality of can holders, each comprising a stationary and a movable clamping head, means including a bell crank member and a toggle connection for actuating the movable head of each holder, a post slidably carried by each bell crank member, means for yieldably holding said posts against displacement, a cam in the path of travel of said posts for closing the holders, a cam in the normal path of travel of said posts for opening the holders, and a cam in the path of 110 travel of said posts when moved from normal position for opening said holders.

6. In a can testing machine, the combination of a rotatable carrier provided with a plurality of can holders, a tank in which the lower portion of said carrier is submerged, means for feeding cans to said carrier at one side of the tank, means for clamping the cans in said holders, a discharge chute at one side of said tank, kick-out mechanism for discharging the cans from said carrier into said discharge chute, and a drip plate mounted beneath the upper portion of said carrier.

7. In a can testing machine, the combina-

- tion of a rotatable carrier provided with a plurality of can holders, a tank in which the lower portion of said carrier is submerged, means for feeding cans to said carrier at one side of the tank, means for clamping the cans in said holders, a discharge chute at one side of said tank, kick-out mechanism for discharging the cans from said carrier into said discharge chute, 10 a drip plate mounted beneath the upper portion of said carrier, and common means for supporting said kickout mechanism and said drip plate.
8. In a can testing machine the combination of a rotatable carrier provided on its periphery with a series of can holders, a hollow stationary shaft concentric with said carrier, a disk provided with a single port, fixed on said shaft, means for supplying air 20 under pressure to the shaft, a connection between the interior of the shaft and the port in said disk, a plate rotatable with the carrier in contiguous relation to said disk, said plate being provided with a series of 25 ports adapted to successively register with said disk port, a connection between each plate port and its respective can holder, and means for yieldingly urging said plate toward said disk.
- 30 9. In a can testing machine the combination of a stationary hollow shaft, means for supplying air to one end thereof, a normally
- stationary disk adjustably mounted on said shaft and provided with an elongated port, means for connecting said port with the interior of said shaft, a carrier provided with a plurality of can holders rotatable concentrically with said shaft, a plate connected to said carrier to rotate therewith, said plate being movable axially of said shaft relatively to the carrier, means for connecting each of said plate ports with its respective can holder, and springs interposed between said carrier and said plate for maintaining a sealing relation between said plate and 45 said disk.
10. In a can testing machine the combination of a stationary hollow shaft, a tubular shaft rotatable about said hollow shaft, a carrier fixed to said tubular shaft, a disk 50 adjustably fixed to said stationary shaft, a plate slidably doweled to said carrier, springs for urging said plate into sealing relation with said disk, said disk being provided with a single port and said plate being provided with a series of ports adapted to successively register with said disk port, a connection between the interior of said shaft and said disk port, a plurality of can 55 holders mounted upon the periphery of said carrier, and a connection from each plate port to its respective can holder.

WILLIAM CAMERON.
